UNITED STATES PATENT OFFICE.

FREDERICK G. ALFORD, OF ISSAQAH, WASHINGTON, ASSIGNOR OF ONE-HALF TO PHILO M. WILLIAMS, OF SEATTLE, WASHINGTON.

RAIL-FASTENER.

No. 890,116.

Specification of Letters Patent.

Patented June 9, 1908.

Application filed May 22, 1907. Serial No. 375,065.

To all whom it may concern:

Be it known that I, FREDERICK G. ALFORD, a citizen of the United States, residing at Issaquah, in the county of King and State of Washington, have invented certain new and useful Improvements in Rail-Fasteners, of which the following is a specification, reference being had therein to the accompanying drawings.

10 This invention relates to the construction of railway tracks; and its object is the provision of simple and efficient means for securing the rails upon the cross ties.

15 The invention consists in the novel construction, arrangement and combination of parts as will be hereinafter described and claimed.

20 Figure 1 is a side elevation of a cross-tie, with the track rails and a pair of the clamping devices therefor shown in section; Fig. 2, a plan view of two ties with the rails attached thereto; Fig. 3, an end elevation of Fig. 1; and Fig. 4, a perspective view of a rail clamp shown detached.

25 In these drawings, the reference numeral 5 designates the track rails and 6, metallic cross-ties which are desirably of the I-beam type and seated in a concrete bed 7. To furnish a more resilient bearing for the rails 30 than would be had if seated directly upon the ties, I provide cushioning seats 8 of vulcanized vegetable fibers, or an equivalent resilient substance, between the ties and the rails at their respective crossings. The 35 rails are secured in place by clamping members, see Fig. 4, which are adapted to engage the flanges of the rails and also the top flanges 6' of the ties. Specifically, these members are severally comprised of a central web 9 40 formed with pendent wings 9' extending along its opposite lateral edges but of less length so that the web will have a protruding nose 9".

45 Extending inwardly from the wings are studs 10 which are in axial alinement with each other and disposed adjacent to the nose end of the member and likewise so that there will be space enough thereabove to allow the flanges of a tie being freely introduced between the same and the web 9. In proximity of the end opposite said nose a screw-threaded aperture 11 is provided in the web for the reception of a clamping screw 12 and which screw is provided with a lock-nut 13. 55 In practice, notches 6" are provided in the

flanges 6' intermediately of the length of said ties to accommodate the studs 10 when introducing the clamping members between rails previously set upon the ties.

The mode of operation of the invention is 60 as follows: The rails being first placed in correct alinement upon the ties with the elastic material therebetween, as aforesaid, the clamping members are placed upon the ties with their studs below the tie-flanges and 65 thus brought against the rail so that the noses 9" will overhang the adjacent rail-flanges and the ends of the wings contact with the edges of the latter. The clamping members being thus positioned, they are 70 caused to effect the clamping of the rails by tilting the members to have their respective noses press downwardly upon the rail flanges through the action of the screws 12, whereupon the screws are secured against unlock- 75 ing by the nuts 13.

By reason of the relative disposition of the nose, fulcrum studs and screw it is evident that an exceedingly great pressure may be imparted and maintained by the clamping 80 members upon the rail flanges and thus reliable means furnished for securing rails to ties. It is further evident that the wings of the clamping members by engaging against the rail flanges prevent lateral displacement 85 of the rails. The members are readily disengaged by first loosening the locking nuts and then retracting the screws.

The above described invention is not only capable of reliably holding rails, but may be 90 inexpensively made, and quickly applied and disengaged.

What I claim as my invention, is—

1. A clamping device for track rails comprising a central web provided with wings 95 extending along a portion of its lateral edges, studs extending inwardly from said wings, and a screw extending through said web.

2. In combination with a track rail, a cross-tie having a lateral flange at its top, 100 and a sheet of resilient material between said rail and said tie, of a device for clamping the rail to the tie, and consisting of a member adapted to engage the rail flange upon the top and the tie-flanges from their under 105 sides, and means to tilt the member and to cause it to effect such engagements with the respective flanges.

3. In combination with a track rail and a cross-tie having lateral flanges, of means for 110

securing said rail to the tie and comprising a member provided with a web having at one end a nose adapted to overlie a flange of the rail, studs projecting inwardly from wings 5 formed upon said web, a screw passing through the web and impinging against said cross-tie for tilting the member to cause said nose to engage the track rail flange, and a

lock-nut for securing said screw in engaged position.

In testimony whereof I affix my signature in presence of two witnesses.

FREDERICK G. ALFORD.
